HEAT TREATMENT OF SOLID CARBON- CONTAINING MATERIALS

George H. Palmer, Fanwood, N. J., and Cruzan Alexander, Jackson Heights, N. Y., assignors to The M. W. Kellogg Company, Jersey City, N. J., a corporation of Delaware

Application October 28, 1948, Serial No. 57,083
16 Claims. (Cl. 260—449.6)

This invention relates to the heat treatment of solid carbon-containing materials. In one aspect this invention relates to a method for the manufacture of a gas containing hydrogen and carbon monoxide. In another aspect this invention relates to an integrated process for the gasification of solid carbon-containing materials and the synthesis of organic compounds. Although the invention is described with respect to the conversion of coal or coke, in its broadest aspects the invention also relates to similar conversion of other types of solid carbon-containing materials, such as sub-bituminous coal, lignite, peat, and shale.

It has been known that coal may be treated with oxygen and steam in a reaction zone at relatively high temperatures to convert the coal to hydrogen and carbon monoxide, which products are useful for various purposes such as fuel or as a feed gas for the synthesis of organic compounds. In general, the coal or coke is contacted with steam in a reaction zone at a temperature above about 1000° F. The operating conditions employed are such that a substantial proportion of the steam reacts with coal to produce hydrogen and carbon monoxide, the production of which products is favored by high temperature.

It has been proposed to maintain the required temperature for the gasification of the coal by simultaneously introducing oxygen with the steam into the gasification zone. The temperature of reaction recommended was not always that best suited for the production of the maximum amount of carbon monoxide. For example, relatively low temperatures were proposed as being practical because of the economic advantage gained in the saving of oxygen and in order to obtain a fuel gas having methane which increased the heating value of the resulting gas. Working at these lower temperatures would inevitably result in the production of some carbon dioxide at the expense of carbon monoxide. The production of carbon dioxide is favored at lower temperatures by both the steam-coal reaction and the oxygen-coal reaction. Carbon dioxide thus produced would constitute a loss of carbon and oxygen and would usually require separation of the carbon dioxide from the product gas, which removal would be a costly operation. It is much to be desired, therefore, to provide a process which may operate at the relatively low temperatures for reasons of economy and/or in order to produce a high heating value gas, and yet which process substantially reduces or minimizes the amount of carbon dioxide produced under such conditions.

The object of this invention is to provide a gasification process operable at relatively low temperatures with the minimum production of carbon dioxide.

Still a further object of this invention is to provide an integrated process for the gasification of coal and for the conversion of the products therefrom to normally liquid organic compounds.

It is another object of this invention to provide a process to produce a high heating value fuel gas ac-

2

companied by the minimum amount of carbon dioxide formation.

A further object of this invention is to provide a process for the gasification of low grade carbon-containing solid materials which are ordinarily unsuitable for other types of gasification processes, particularly when used in a suspended condition.

Another object of this invention is to provide a method for removal and separation of ash and like undesirable material from a process for the gasification of carbon-containing solid materials.

An object of this invention is to provide a gasification process in which volatile components of the solid carbon-containing materials may be recovered.

A further object is to provide a gasification process which is substantially more economical than previously proposed processes.

Various other objects and advantages of the present invention will become apparent to those skilled in the art from the accompanying description and disclosure.

According to the improved process of this invention, carbon-containing solid material and any accompanying hydrocarbon are reacted with steam in a reaction zone under optimum endothermic conditions such that hydrogen and carbon monoxide are produced. In another separate reaction zone, carbon-containing solid material, any accompanying carbon dioxide and oxygen are reacted under optimum exothermic conditions such that carbon monoxide is produced as a principal product of the reaction. In order to supply heat to the endothermic reaction, solid carbon-containing material is circulated between both the exothermic and endothermic reaction zones. The circulation of solids between the reaction zones maintains each zone at the desired temperature level when properly operated in accordance with this invention. The reaction effluents from each zone are combined as a product of the process for such uses as fuel or as feed gas to an organic synthesis process. Oxidation of coal is effected in the exothermic reaction zone with free oxygen at a temperature between about 1800 and 2000° F., which temperature conditions are the optimum for the conversion of coal to carbon monoxide at about atmospheric pressure. Excess coal is present in this reaction zone. Heat of reaction is absorbed by the excess coal, which is circulated to the endothermic reaction zone. In the endothermic reaction zone, steam is reacted with coal at a temperature at least 200° F. lower than the temperature of reaction in the exothermic reaction zone, which conditions are more favorable at about atmospheric pressure to the formation of hydrogen and carbon monoxide than at the higher temperatures of the exothermic reaction zone. When it is desired to produce hydrogen and carbon monoxide with the minimum amount of other products by the steam-coal reaction at about atmospheric pressure, a temperature between about 1500 and about 1700° F. is employed. When it is desired to produce a high heating value gas containing substantial proportions of methane at about atmospheric pressure, a temperature below about 1500° F., preferably not lower than 1300° F., is employed in the endothermic reaction zone.

A sufficient quantity of coal is circulated from the exothermic reaction zone at the temperature level prevailing therein to the endothermic reaction zone such that the temperature of the endothermic reaction zone is maintained at the desired level by liberation of the sensible heat of the coal circulated. In continuously effecting the process, the quantity of coal and oxygen employed in the process must be adjusted such that the required temperature is maintained in the exothermic reaction zone and such that the desired temperature in the endothermic reaction zone may be obtained from the

sensible heat of the coal circulated thereto. Conveniently, unconverted coal or coke from the endothermic reaction zone is returned to the exothermic reaction zone for further conversion thereof; fresh coal being added to the process at the desired point in the system, either intermittently or continuously.

The preferred method of operation is by the use of the so-called "fluidized" technique in which the coal is in a finely-divided form and present in the reaction zone in a conventional fluidized pseudo-liquid condition. Gaseous reactants and products are passed upwardly through a mass of finely-divided coal at a sufficient velocity to maintain the coal in such a fluidized condition whereby the finely-divided particles of coal circulate throughout a dense phase in the lower portion of the reaction zone. The use of the "fluidized" technique also has the advantage of substantially uniform temperature conditions within the fluidized mass because of the high heat transfer rate between the gas and solid particles. Fluidized coal or coke is circulated between the reaction zones by means of conventional methods, such as by the use of aerated standpipes of sufficient length to overcome pressure drops or by the use of solids pumps, such as a Fuller-Kinyon pump.

In this type of operation the coal is used in a finely-divided form, preferably a major proportion of the coal has a particle size less than about 250 microns. The finely-divided condition of the coal may be obtained by crushing and grinding large pieces of coal in suitable equipment, such as a ball mill, or by explosion pulverization.

It is believed that the present invention may be best described by reference to the accompanying drawings which show the inventive features of the present invention as applied, for example, to the synthesis of organic compounds and to the production of a fuel of high heating value.

Figure 1 of the drawings is a diagrammatic illustration in elevation of an arrangement of apparatus for the synthesis of organic compounds embodying the present invention in which the coal in the gasification step is maintained in a fluidized pseudo-liquid dense phase condition in both the exothermic and endothermic reaction zones.

Figure 2 of the drawings is a modification of the operating technique shown in Figure 1 and illustrates an arrangement of apparatus for the operation of the invention in which the coal is carried in the gaseous reactants in a relatively less dense condition than the conventional dense phase of Figure 1.

Figure 3 of the drawings is a diagrammatic illustration in elevation of an arrangement of apparatus for the production of a fuel gas of high heating value embodying teachings of the present invention in which finely-divided coal in the gasification step is maintained in a pseudo-liquid dense phase condition.

Figures 4 and 5 illustrate modifications of the present invention for the introduction of fresh coal into the system and the removal of ash from the system.

Referring with particularity to Figure 1 of the drawings, an oxygen-containing gas, such as substantially pure oxygen or enriched air, is passed by means of conduit 4 through a conventional heat exchanger 28 to conduit 6. Coal or coke is introduced into conduit 6 and mixed with the oxygen-containing gas, and the resulting mixture is passed to partial combustion chamber 7, which comprises a conventional cylindrical chamber having a refractory lining. Oxygen is passed upward through a mass of finely-divided coal or coke in chamber 7 at a velocity sufficient to maintain the finely-divided solids in a fluidized pseudo-liquid condition characterized by an interface 8 between a lower dense phase and an upper relatively dilute phase. Sufficient oxygen is utilized in proportion to the mass of coal or coke that a uniform temperature between about 1800 and about 2000° F.

is maintained in chamber 7 at approximately atmospheric pressure. A suitable oxidation temperature in chamber 7 is about 1900° F. Under the conditions utilized in chamber 7 coal is converted to a major proportion of carbon monoxide and a minor proportion of carbon dioxide. However, under the temperature conditions employed in chamber 7 a minimum amount of carbon dioxide is produced, in some instances less than about one per cent of the product gases. An effluent gas containing carbon monoxide and some entrained ash and unburned coal or coke is passed to a solids separator 11 which may comprise a conventional cyclone separator. If desired, a cyclone separator or ceramic filters may be positioned within chamber 7 to at least partially remove entrained coal and ash. Since the ash is a relatively lighter material than the coal, the solids withdrawn from reactor 7 through conduit 9 contain a higher proportion of ash than present in the dense phase. Hence, permitting solids to pass overhead from reactor 7 and separating them from the effluent in separator 11 is a convenient and effective manner of preventing the build-up of ash in the system. Solids thus separated are withdrawn from separator 11 through conduit 26.

Finely-divided coal and/or coke at a relatively high temperature is withdrawn from the dense phase of chamber 7 through a conduit or standpipe 13 and introduced into a gas stream consisting essentially of steam passing through conduit 16. An aerating or stripping gas, such as steam, carbon dioxide, or recycle gas from the synthesis step to be discussed further hereinafter, may be introduced into conduit or standpipe 13 for aerating and/or stripping the solid particles therein. Steam is introduced into the system through conduit 16 and may be by-passed through conduit 17 to heat exchanger 28 for superheating. The resulting mixture of steam and solids withdrawn from chamber 7 are passed through conduit 16 to a gasification chamber 18, which comprises a conventional cylindrical reaction chamber similar to that of chamber 7. Alternatively or additionally to coal introduced into the system through conduit 6, fresh coal may be introduced into conduit 16 by means of conduit 24. This may be a particularly desirable location for introducing coal, since the coal is contacted at this point at a temperature somewhat lower than that existing in chamber 7. Volatile components are distilled from the coal at a temperature at which the tendency for their decomposition is minimized. The relatively low temperature at this point also reduces the tendency of the fresh coal to fuse and the finely-divided particles to agglomerate or stick together.

The finely-divided coal in chamber 18 is maintained in a fluidized condition characterized by an interface 19 between a lower dense phase and an upper dilute phase similar to that described with respect to chamber 7. For the production of a gas of optimum composition with respect to hydrogen and carbon monoxide by the steam-coal reaction, the temperature of chamber 18 is maintained between about 1500 and about 1700° F. at atmospheric pressure by regulating the temperature and quantity of the solids circulated from chamber 7 to chamber 18. Under the optimum conditions maintained in chamber 18 steam is reacted with the coal or coke to produce hydrogen and carbon monoxide with a minimum formation of carbon dioxide, methane and water vapor, usually less than 5 per cent, in the product. An effluent comprising hydrogen and carbon monoxide and entrained coal or coke and ash is removed from chamber 18 through conduit 21 and is passed to separator 11 as previously discussed. Ash and coal are separated from the effluent and removed from separator 11 through conduit 26. As in the case of chamber 7, a cyclone separator or ceramic filters may be positioned within chamber 18, in addition to or substitution for, as the case may warrant, separator 11 for removing at least a portion of the entrained solids from the effluent. Unconverted coal

or coke may be removed from chamber 18 through conduit or standpipe 22 and may be recirculated to chamber 7 by introduction into conduit 6. A stripping and/or aerating gas, such as steam or methane, may be introduced into conduit 22 through conduit 23, if desired. Fuller-Kinyon pumps may be used in place of the standpipes of this process without departing from the scope of this invention.

The mol ratio of oxygen to steam introduced into the system is between about 0.3 and about 0.7. Pressures between about atmospheric and about 1500 pounds per square inch gage may be employed without departing from the scope of this invention. Pressures below about 150 pounds per square inch gage are preferred, however. At elevated pressures somewhat higher temperatures are necessary for the respective reaction zones in order to prevent the increased production of undesirable by-products. In general, partial combustion chamber 7 is operated at a temperature corresponding to a temperature between 1800 and about 2000° F. for atmospheric pressure operations, and gasification chamber 18 is operated at a temperature corresponding to about 1300 to about 1700° F. for atmospheric pressure operations. Excess coal is employed in the system to supply sufficient heat carrier material for transferring a portion of the exothermic heat of reaction from chamber 7 to chamber 18.

A gaseous effluent comprising hydrogen and carbon monoxide in a ratio of about 0.5:1 to about 2:1 at a temperature usually above about 1500° F. when producing a synthesis feed gas is removed from solids separator 11 and passed through conduit 27 to heat exchanger 28 in which a portion of its heat is given up to the reactants. From heat exchanger 28 the gaseous effluent containing some unconverted steam is passed to synthesis reactor 31 through conduit 29. Steam may be removed from the reaction effluent in conduit 29, when it is present in excess of that permissible or desirable for the synthesis reaction, by further cooling thereof by means not shown, such as by a conventional waste heat boiler or a liquid scrubbing tower.

In synthesis reactor 31, the synthesis feed gas passes upwardly through a mass of finely-divided catalyst such as a metal of group VIII of the Periodic Table, for example reduced iron or cobalt, under suitable operating conditions for the conversion of hydrogen and carbon monoxide to normally liquid organic compounds comprising hydrocarbons and oxygenated organic compounds. When using reduced iron as the catalyst a temperature between about 550 and about 750° F. is employed, and preferably a pressure corresponding substantially to, or somewhat lower than, the pressure employed in the gas-making step. Higher pressures, up to as high as 700 pounds per square inch gage, may be employed. When pressures are employed in synthesis reactor 31 which are above the pressure employed in the gas-making step, a suitable compressor must be used. The mass of finely-divided catalyst in reactor 31 is maintained in a fluidized condition characterized by an interface 32 between a lower dense phase and an upper relatively dilute phase. Catalyst is withdrawn from the dense phase of reactor 31 through conduit or standpipe 34 and passed through a conventional catalyst cooler 36 and reintroduced into conduit 29. The temperature of synthesis reactor 31 may be controlled within relatively narrow limits by removal of exothermic heat of reaction by means of catalyst cooler 36. Catalyst may be withdrawn through conduit 37 for regeneration, such as by oxidation and reduction, and subsequently returned to reactor 31 by means not shown.

Synthesis reactor 31 may be cooled also by indirect cooling means positioned within the dense phase, if desired. A suitable vaporizing or cooling liquid may also be introduced directly into the dense phase for cooling purposes. A cyclone separator or filters may be posi-

tioned within or externally of reactor 31 to remove entrained catalyst from the reaction effluent.

A reaction effluent comprising hydrogen, carbon dioxide, methane and higher boiling hydrocarbons, and oxygenated organic compounds is removed from reactor 31 and passed through conduit 33 to a conventional recovery unit shown diagrammatically at 38. Recovery unit 38 may comprise a single or series of condensers and accumulators or fractional distillation columns with suitable auxiliary equipment for the separation and recovery of the products of the process. Water is withdrawn from recovery unit 38 through conduit 39 and may be subjected to further treatment to recover oxygenated chemicals therefrom. Organic products, such as hydrocarbons and oil-soluble oxygenated chemicals, are removed from recovery unit 38 through conduit 41. Uncondensed vapors, such as hydrogen, carbon dioxide and methane, are removed from recovery unit 38 through conduit 42 and may be passed directly to conduit 17 for introduction into gasification chamber 18. It is preferred to introduce methane into gasification chamber 18 so that it can be reformed with steam therein to produce hydrogen and carbon monoxide.

All or a portion of the uncondensed vapors from recovery unit 38 may be passed through conduits 42 and 43 to a conventional carbon dioxide absorption unit 44 comprising an absorption tower in which the uncondensed vapors are counter-currently contacted with a suitable absorption liquid, such as an amine solution. Unit 44 further comprises a desorption zone in which the absorbing liquid containing absorbed carbon dioxide is subjected to conditions of temperature and pressure to desorb the carbon dioxide. Gases substantially free from carbon dioxide and containing methane are removed from absorption unit 44 and may be passed, if desired, through conduit 47 to conduit 42 for circulation to gasification chamber 18. Carbon dioxide recovered in unit 44 is removed therefrom through conduit 48 and may be recycled to conduit 4 by means not shown for introduction into partial combustion chamber 7. Carbon dioxide in combustion chamber 7 is converted to carbon monoxide. When the gases in conduit 42 contain a major proportion of carbon dioxide, or when carbon dioxide is separated from such gases, the carbon dioxide or carbon dioxide rich gases are preferably passed to combustion chamber 7 in which optimum conditions exist for the conversion of carbon dioxide to carbon monoxide.

It is within the scope of this invention to pass a portion of the vapors from recovery unit 38 through conduit 42 directly to gasification chamber 18, and to simultaneously pass another portion of these vapors to absorption unit 44. In this modification, carbon dioxide is separated in recovery unit 44 and is separately passed through conduit 48 to partial combustion chamber 7 while the carbon dioxide free stream containing methane is returned from absorption unit 44 through conduit 47 to conduit 42.

In order to prevent the build-up of nitrogen in the system, particularly when enriched air is used as the oxygen-containing gas, a portion of the vapors in conduit 42 or conduit 47 are vented to the atmosphere. Air itself may be used as the oxygen-containing gas in line 4 without departing from the scope of this invention, and under such circumstances a large proportion of the vapors in conduit 42 is vented to the atmosphere.

In the operation of Figure 1 described above the sole source of heat is the partial combustion of coal in chamber 7. However, external heating means may be provided in addition to the partial combustion of coal for producing heat. Such external means may comprise preheating furnaces for the steam and/or oxygen-containing gas. A catalytic material or heat-carrying material, such as an ore, may be used in combination with the coal in chambers 7 and 18 without departing from the scope of this invention. For example, an iron ore con-

taining magnetite may be admixed with the coal introduced into conduit 6 or introduced through conduit 24. The magnetite promotes the production of hydrogen and carbon monoxide and also serves as a heat-carrying material for the flow of heat from partial combustion chamber 7 to gasification chamber 18.

Various methods may be utilized to obtain the finely-divided condition of the coal for use in a fluidized process described with respect to Figure 1. The coal may be crushed first in a jaw crusher and then ball-milled to the desired size. Alternatively, the coal may be introduced into a stream of steam which is injected into the system, by reducing the pressure at least 50 to 100 pounds, thereby pulverizing the coal by explosion pulverization (expansion of the steam in the pores of the coal).

Figure 2 of the drawings is a modification of the invention in which gasification chamber 18 of Figure 1 is operated with a sufficiently high linear gas velocity therein that the net movement of the coal is in the direction of flow of the gas stream passing therethrough as a result of the gas velocity. The description of Figure 2 will be brief, since the operating conditions may be substantially the same as those described with respect to Figure 1, and it should be understood that the product gas obtained therefrom may be utilized for the synthesis of organic compounds in the manner described with respect to Figure 1. Steam passes through conduit 61 and heat exchanger 82 to gasification chamber 62, which comprises an elongated conduit generally of relatively small diameter as compared to the chamber 18 of Figure 1. The steam in conduit 61 picks up hot coal or coke from conduit 76 and the resulting mixture is converted to hydrogen and carbon monoxide in chamber 62. Additionally, steam may be introduced longitudinally at spaced intervals along chamber 62 through conduits 66, 67, and 68, as shown, to aid in maintaining the desired concentration of steam at any particular point in chamber 62. The velocity of the gases in chamber 62 is preferably above 5 feet per second, usually between 8 and about 40 feet per second, depending on such factors as particle size and density, reaction conditions, etc., such that the finely-divided coal or coke moves in the direction of the flowing gases and may at very high velocities travel at substantially the same rate as the gases. The concentration of the coal in the gases is much less than the concentration of coal in a conventional pseudoliquid dense phase, which is usually 20 pounds per cubic foot of gas or greater, and for this reason sticking and agglomeration of the coal or coke is minimized. The concentration of finely-divided solids is generally in the range of about 1 to about 10 pounds per cubic foot of gas. Unconverted coal or coke, ash, hydrogen, carbon monoxide, and steam are withdrawn from gasification chamber 62 through conduit 63 and are passed at the above relatively high velocity to separator 64. Separator 64 may comprise a conventional settling zone, a cyclone separator, or the like, for separation of unconverted coal or coke and ash from the gasification effluent. Since the gasification effluent in conduit 63 is at a relatively low temperature because of endothermic reaction in chamber 62, it may be desirable to introduce fresh coal into the process into conduit 63 through conduit 69. In this manner the fresh coal contacts the gases of the process at the minimum temperature whereby the valuable vaporizable products of the process are distilled without substantial cracking thereof. Moreover, since the stream of gases in conduit 63 is at a relatively high velocity and the solids are well dispersed therein, the tendency for the fresh coal to agglomerate and stick is minimized. It is therefore a particular feature of this invention to introduce fresh coal into the high velocity effluent stream from chamber 62 and maintain the coal therein long enough to substantially completely distill vaporizable components from the fresh coal. Thus, the

length of conduit 63 may be adapted to achieve sufficient holding time for distillation of the fresh coal.

Separated coal is passed from separator 64 into partial combustion chamber 72 by gravity. Oxygen is introduced into partial combustion chamber 72 at a plurality of points spaced longitudinally along chamber 72, such as by means of conduits 73 and 74, in order to minimize "hot spots" or local overheating. In partial combustion chamber 72 coal or coke is converted to carbon monoxide and carbon dioxide accompanied by liberation of heat. Coal and/or coke is withdrawn from gasification chamber 72 at a relatively high temperature by means of standpipe 76. The quantity of oxygen and the shape of chamber 72 is such that a sufficiently high upward gas velocity is maintained therein to maintain the finely-divided coal or coke in a fluidized pseudo-liquid condition similar to that described with respect to combustion chamber 7 of Figure 1. The velocity may be sufficiently low that little, if any, circulation of the solids in the dense phase is obtained. In this modification the solids flow substantially countercurrently to upflowing gases. A portion of the finely-divided coal and/or coke is withdrawn from chamber 72 through conduit 78 to prevent the build-up of ash in the system. Ash may be separated from unconverted coal or coke withdrawn through conduit 73 and the separated unconverted material returned to the process, if desired.

In order to produce a maximum amount of hydrogen and methane from the coal, fresh coal is preferably introduced directly into separator 64 through conduit 77. In this manner the fresh coal is contacted with the hot gases from partial combustion chamber 72, which gases are at a relatively high temperature favorable to the conversion of the volatile components of the coal to hydrogen and methane.

An aerating or stripping gas may be introduced into standpipe 76 through conduit 83. Such aerating or stripping gas may comprise recycle gases, carbon dioxide, or oxygen. When stripping is effected in conduit 76 to remove occluded carbon monoxide, a relatively larger proportion of gas is introduced into conduit 83 than when mere aerating is effected in conduit 76 to assure free flow of solids therethrough.

A gaseous effluent comprising hydrogen, carbon monoxide, carbon dioxide, and unconverted steam is removed from separator 64 through conduit 81 and is passed through heat exchanger 82. The effluent gases in conduit 81 may be passed to a synthesis reactor, as described in Figure 1, or may be used as a fuel gas. When the coal contains valuable volatilizable components and is introduced into the system through conduit 69 the effluent gases in conduit 81 are passed to a cooling system for condensation and recovery of water and valuable organic components of the coal, such as tars, naphthalene, anthracene, benzol, toluol, phenol, cresol, xylol, and normally gaseous and liquid hydrocarbons, as well as some nitrogen and sulfur compounds.

Figure 3 of the drawings, illustrating another embodiment of the present invention, diagrammatically shows in elevation an arrangement of apparatus for the production of a fuel gas of high heating value in accordance with the teachings of this invention. A gaseous stream comprising oxygen or a mixture of oxygen and other gases, such as carbon dioxide, is passed through conduit 91 to a partial combustion chamber 92. Recycle coal is introduced into the gas stream in conduit 91 by means of conduit or standpipe 102 and is carried to chamber 92. As explained in the discussion of chamber 7 of Figure 1, gasification chamber 62 is operated at optimum exothermic conditions for the conversion of coal or coke to carbon monoxide accompanied by the liberation of heat. The preferred temperature range for gasification chamber 92 is between about 1800° and about 2000° F. The gas is passed upward through chamber 92 at a velocity sufficient to suspend the coal in a so-called pseudo-liquid

dense phase in which the fine solid particles circulate throughout the dense phase. A gaseous effluent comprising carbon monoxide and containing ash and in some cases entrained coal or coke is passed through conduit 93 and a conventional heat exchanger or cooler 94 and thence to a solids separator 96. The gaseous effluent from chamber 92 is cooled by heat exchanger 94. Solids separator 96 may comprise any conventional type of separating means for separating solids from gases, such as an enlarged settling zone or a cyclone separator.

Cyclone separators or filters may be positioned within chamber 92 to at least remove a portion of the entrained solids carried with the gaseous effluent. However, with the use of cyclone separators within chamber 92, additional means, such as separator 96, is usually employed to remove additional entrained solids, particularly ash.

Coal and/or coke at a relatively high temperature is removed from combustion chamber 92 by means of standpipe 97 and passed to conduit 98. Water is introduced into conduit 98 and passes through a heater or heat exchanger 99 in which the water is vaporized and steam thus produced is superheated. Steam passing through conduit 98 picks up hot coal which further heats the steam to the desired temperature by virtue of the higher temperature and the quantity of coal circulated. The resulting mixture of superheated steam and coal is passed through conduit 98 to gasification chamber 101 which is operated in a similar manner as chamber 92. The quantity of steam and the shape and size of chamber 101 are such that the upward linear gas velocity is sufficient to maintain the finely-divided coal in a pseudo-liquid dense phase condition therein.

In this embodiment of the invention, a high heating value gas is produced which contains a substantial portion of methane. The production of methane is favored at lower temperatures, but at such temperatures the formation of methane is also accompanied by the formation of carbon dioxide. It is a particular advantage of the present process, therefore, that the oxidation reaction and the steam-coal reaction can be carried out in separate reaction zones. Thus, the additional carbon dioxide which would be formed by the oxygen-coal reaction at the lower temperatures necessary for methane formation is eliminated. The temperature of reaction in chamber 101 is maintained between about 1300 and about 1500 for the formation of methane, hydrogen and carbon monoxide together with small proportions of carbon dioxide.

A gaseous effluent comprising hydrogen, carbon monoxide, carbon dioxide, methane, and entrained ash and in some instances coal or coke is removed from chamber 101 through conduit 103 and may be passed directly through conduits 103 and 111 to solids separator 96 for separation of the solids from the effluent.

In the preferred modification of Figure 3, fresh coal is introduced directly into chamber 101 by means of conduit 129. The effluent in conduit 103 will then contain also volatile components of the coal and is passed through conduit 104 to a separator 106 which comprises a cooler and an accumulator for condensing liquid products, which in most instances are the volatile components of the coal, are withdrawn from separator 106 through conduit 107 as by-products of the process. Undecondensed components of the effluent including methane, hydrogen, carbon monoxide and carbon dioxide are passed from separator 106 through conduit 108 to a conventional carbon dioxide absorber 109.

In carbon dioxide absorber 109, the gaseous stream is passed upwardly in countercurrent contact with an absorption liquid, such as an amine solution. Substantially all of the carbon dioxide is removed from the effluent in absorber 109. A gas consisting essentially of hydrogen, carbon monoxide and methane is removed from absorber 109 and passed through conduit 111 to

separator 96 to be combined with the effluent from chamber 92. A high heating value gas comprising hydrogen, carbon monoxide and methane substantially free from carbon dioxide and volatile components of the coal is removed from separator 96 through conduit 121 as the product of the process.

In most instances the removal of carbon dioxide from the effluent of chamber 92 is unnecessary because of the relatively small amount produced in chamber 92. In 10 case it should be desirable to remove carbon dioxide from the effluent in conduit 93, this effluent may be passed to absorber 109 by means not shown, or a separate absorber on conduit 93 may be employed.

Absorption liquid rich in carbon dioxide is removed 15 from absorber 109 through conduit 113 and is passed to a desorption zone 114. In desorption zone 114, carbon dioxide is removed from the absorption liquid by regulating the temperature and pressure conditions therein in a manner known to those skilled in the art. Lean absorption liquid is removed from desorption zone 114 through conduit 117 and returned to absorption chamber 109 through conduit 118. Fresh absorption liquid may be introduced into absorption chamber 109 through conduit 118. Desorbed carbon dioxide is removed from desorption zone 114 through conduit 116 and may be introduced into conduit 91 for recycle to combustion chamber 92. The carbon dioxide thus produced in gasification chamber 101 is converted to carbon monoxide in combustion chamber 92.

As in the case of combustion chamber 92, a cyclone separator or filters may be positioned within chamber 101 to at least partially remove entrained coal or coke and ash from the reaction effluent.

Ash and coal separated from the effluents by separator 96 are removed therefrom through conduit 119 for disposal or recirculation to either or both chambers 92 and 101.

Fresh coal is introduced into the process from hopper 127 through either conduit 128 or conduit 129. Coal is introduced directly into combustion chamber 92 through conduit 128, or directly into gasification 101 through conduit 129. Whether the coal is introduced into chamber 92 or chamber 101 will depend on various factors, such as the type and composition of the carbon-containing material and whether it is desirable to recover the maximum amount of volatile components without the decomposition thereof. Unconverted coal and/or coke is removed from gasification chamber 101 through a standpipe 102 for circulation to combustion chamber 92, as previously discussed.

Upon continuous introduction of coal into the process and the continuous conversion thereof to hydrogen and carbon monoxide, ash tends to build up in the system. In order to limit the build-up of ash to that desirable or permissible, a portion of the coal or coke in chamber 101 is continuously or intermittently removed therefrom through standpipe 122 and is introduced into an elongated reaction chamber or conduit 123. Excess oxygen which may be preheated is introduced into 60 elongated reaction chamber 123 to substantially completely burn the coal. Oxygen, together with an inert gas if desired, is passed through elongated reaction chamber 93 at a sufficient velocity to continuously move the coal or coke and ash in the direction of the flow of the gas stream and at relatively high velocities substantially entrain the solids in the gas. As the coal or coke flows in the direction of flow of the gas stream, it is converted to carbon monoxide and carbon dioxide. The residence time of the coal is maintained by controlling the velocity of the gases and the length of the reactor such that only ash passes from conduit 123 to solids separator 124, the coal being completely consumed by oxidation. In solids separator 124, ash is separated from the gaseous effluent of reactor 123 and is removed from separator 124 through conduit 125 for disposal. Excess

11

oxygen, carbon dioxide and carbon monoxide at a relatively high temperature are removed from separator 124 and passed through conduit 126 and heat exchanger 99 to combustion chamber 92. The effluent from reactor 123 may supply the necessary oxygen and heat for the conversion of coal in chamber 92 to carbon monoxide. The carbon dioxide formed in reactor 123 is converted to carbon monoxide by contact with coal in chamber 92, thus making substantially complete utilization of the coal and of the oxygen of the system.

Reactor 123 may be positioned vertically, horizontally, or angularly without departing from the scope of this invention. It is preferred, however, to position elongated chamber 123 vertically using an upward gas velocity therein above about 5 feet per second to move the coal and ash in the direction of the gaseous stream.

The effluent from chamber 101, such as that in conduit 103 or 104, may be heat exchanged with the water in conduit 98 to utilize the heat content of that stream. Various other process streams may be heat exchanged without departing from the scope of this invention. Chamber 101 may also be operated similar to chamber 62 of Figure 2 in which the solids move in the direction of flow of the gases. In such instance, separators, etc., must be provided for removing entrained solids as described in Figure 2.

An important feature of the present invention is the introduction of fresh solid carbon-containing material into the system at any point at which conditions are best suited for the particular solid and the desired results to be obtained. The point of introduction of the solids, such as fresh coal, into the system will depend upon various factors such as the type of coal, i. e., the ash content and fusion temperature thereof, whether it is desirable to recover the volatile components of the coal without substantial cracking and the particular temperature prevailing at the point of introduction of the coal. In Figure 1, fresh coal is introduced into the inlet line 6 to partial combustion chamber 7 and/or inlet line 16 of gasification chamber 18. In Figure 2, fresh coal is introduced into the high velocity outlet gas stream of gasification chamber 62 and/or into the gaseous effluent from partial combustion chamber 72. In Figure 3, fresh coal is introduced directly into partial combustion chamber 92 and/or gasification chamber 101. Several other modifications for introducing the coal may be practiced. For example, Figure 4 of the drawings diagrammatically illustrates a modification of the gasification chamber, such as chamber 18 of Figure 1, or chamber 161 of Figure 3. According to the modification of Figure 4, numeral 131 indicates a cylindrical gasification chamber containing a lower pseudo-liquid gasification chamber containing a lower pseudo-liquid phase 132 of finely-divided solids separated from an upper pseudo-liquid dense phase 133 of fresh coal by means of a perforated plate or screen 134. Steam is introduced into the lower portion of gasification chamber 131 through conduit 136 and coal and/or coke in dense phase 132 is reacted with steam to produce hydrogen and carbon monoxide. Entrained coal and reaction products comprising hydrogen and carbon monoxide pass upwardly through gasification chamber 131 through perforated plate 134 into the pseudo-liquid dense phase of fresh coal 133. Fresh coal is introduced into upper dense phase 133 by means of conduit 137 in the top of chamber 131. The gaseous effluent passing through dense phase 133 is at the minimum temperature for the process and at this temperature the volatile components of the coal are distilled from the coal. A gaseous effluent passes from dense phase 133 and is removed from gasification chamber 131 through outlet conduit 138. This gaseous effluent may be treated in substantially the same manner as described with respect to Figure 3 in order to separate and recover valuable volatile components of the coal. Coal or coke may be removed from upper dense phase 133 and introduced into

12

lower dense phase 132 of gasification chamber 131 by means of standpipe 139 positioned within chamber 131. Alternatively or additionally, coal or coke may be withdrawn directly from the dense phase 133 of chamber 131 by means of outlet conduit 141 and passed to any portion of the system desired, such as directly to a partial combustion chamber (not shown) for the conversion of the coal to carbon monoxide, or to dense phase 132. Also, coal may be removed from the lower dense phase 132 of chamber 131 through a standpipe 142 and may be passed or recycled to a partial combustion chamber (not shown), or treated to remove ash therefrom as described with respect to Figure 3. When coal is passed directly from dense phase 133 to dense phase 132 substantially all of the coal is removed through conduit 142 for recycling to a partial combustion chamber. Upper and lower portions of chamber 131 including the respective dense phases of solids 132 and 133, may be constructed as separate zones suitably connected without departing from the scope of this invention. A suitable aerating or stripping gas may be introduced into conduits 139, 141 and 142.

Figure 5 represents another modification of the present invention which is particularly useful for the recovery of volatile components of the coal with minimum contamination with the gaseous components hydrogen, carbon monoxide and carbon dioxide. In this modification the size of equipment for recovering the volatile components of the coal is minimized. According to the modification shown in Figure 5, numeral 152 indicates a reaction chamber, either a gasification chamber or a partial combustion chamber as previously described. Reactants are introduced into chamber 152 through inlet conduit 151. A reaction effluent containing entrained coal or coke is removed from reaction chamber 152 through conduit 153 and is passed to a conventional solids separator 154. Hot coal or coke is separated from the reaction effluent in separator 154 and is passed through standpipe or conduit 157 to a volatilization chamber 158. The reaction effluent is removed from separator 154 through conduit 156.

In volatilization chamber 158 hot solids from chamber 152 are admixed with fresh coal introduced therein through conduit 161. In this manner the fresh coal is heated to a sufficiently high temperature to distill the volatile components therefrom. An effluent comprising the volatile components of the coal and substantially free from hydrogen, carbon monoxide and carbon dioxide is removed from chamber 158 through outlet conduit 159. This effluent may be passed to conventional separation and recovery equipment (not shown) for the recovery of the volatile components of the fresh coal. A portion of the effluent in conduit 159 is recycled through conduit 161 in order to aid in maintaining the coal in chamber 158 in an aerated or fluidized condition therein. Fresh coal may conveniently be introduced into conduit 161 by means of conduit 162 and thereby injected into chamber 158. The passage of a gas upwardly through chamber 158 intimately mixes the fresh coal with the hot solids from chamber 122, thus maintaining substantial uniform temperature conditions. Coal and/or coke may be intermittently or continuously removed from chamber 158 through conduit 163 and passed to either a gasification chamber or a partial combustion chamber (not shown), as desired. If the coal or coke removed from chamber 158 through conduit 163 is at a higher temperature than the temperature of the gasification chamber, it is preferred to introduce the hot coal into the gasification chamber. However, if the coal or coke removed from chamber 158 is at a lower temperature than the temperature of the gasification chamber of the system, it is best to pass the coal to the partial combustion chamber so that it may be heated prior to circulation to the gasification chamber.

Coal may be passed directly from chamber 152, such as from a dense phase of finely-divided coal therein, to

chamber 158 through conduit 164. Coal or coke may be removed from reaction chamber 152 through stand-pipe 166 for transfer or recycle to other reaction zones of the system, as previously described with respect to the other figures of the drawings.

Reference has been made in many instances to withdrawing coal from the various reaction zones. Actually, coal may not be the technical term for the solids thus removed, as these solids may comprise partially burned coal, coke or mixtures thereof. In the specification and claims, the term coal is intended to include any solid material withdrawn from the reaction zones when coal is the feed material.

Various pumps, coolers, separators and auxiliary equipment have been eliminated from the drawings as a matter of convenience and clarity and their use and location will become apparent to those skilled in the art. Various alterations and modifications of the present invention will become apparent to those skilled in the art without departing from the scope of this invention.

Having described our invention, we claim:

1. A process for producing a gaseous mixture of hydrogen and carbon monoxide which comprises passing steam and finely-divided carbon-containing material through a first reaction zone at a velocity effective to move said finely-divided carbon-containing material as a fluidized mass through said first reaction zone in the direction of flow of the gases therethrough, maintaining in said first reaction zone endothermic conditions of reaction and a temperature between about 1300 and about 1700° F. such that hydrogen and carbon monoxide are produced as the principal products of the reaction between steam and carbon, withdrawing an effluent from said first reaction zone comprising hydrogen, carbon monoxide, entrained ash and unconverted carbon-containing material and passing same at a relatively high velocity of at least 5 feet per second to a solids separator in which solids are separated from the effluent, introducing fresh carbon-containing material into said effluent from said first reaction zone, passing solids from said solids separator into a second reaction zone, passing pure oxygen upward through said second reaction zone at a velocity such that finely-divided solids are maintained in a pseudo-liquid fluidized condition therein, maintaining said second reaction zone under exothermic conditions of reaction at a temperature between about 1800 and about 2000° F. such that a product gas containing a major amount of carbon monoxide and a minor amount of less than about 1% carbon dioxide is produced, the reaction conditions in said second reaction zone have an over-all exothermic effect such that no external heat is necessary to maintain the aforesaid temperature therein, passing an effluent comprising carbon monoxide from said second reaction zone to said solids separator in which the effluents of said first and said second reaction zones are combined, withdrawing a combined effluent comprising hydrogen and carbon monoxide in a mol ratio between about 0.5:1 and about 2:1 from said solids separator as the product of the process, heat exchanging the aforesaid oxygen and steam with the combined effluents prior to charging the same to the reaction zones in the aforesaid manner and removing a sufficient quantity of finely-divided solids from said second reaction zone substantially at the temperature of said second reaction zone and passing same to said first reaction zone to maintain the temperature therein in the above range.

2. A process for producing a gaseous mixture of hydrogen and carbon monoxide which comprises passing steam and finely-divided carbon-containing material through a first reaction zone at a velocity effective to move said finely-divided carbon-containing material as a fluidized mass through said first reaction zone in the direction of flow of the gases therethrough, maintaining in said first reaction zone endothermic conditions of

reaction and a temperature between about 1300 and about 1700° F. such that hydrogen and carbon monoxide are produced as the principal products of the reaction between steam and carbon, withdrawing an effluent from 5 said first reaction zone comprising hydrogen, carbon monoxide, entrained ash and unconverted carbon-containing material and passing same to a solids separator in which solids are separated from the effluent, introducing fresh carbon-containing material into said separator, passing solids from said solids separator into a second reaction zone, passing pure oxygen upward through said second reaction zone at a velocity such that finely-divided solids are maintained in a pseudo-liquid fluidized condition therein, maintaining said second reaction zone under exothermic conditions of reaction 10 at a temperature between about 1800 and about 2000° F. such that a product gas containing a major amount of carbon monoxide and a minor amount of less than about 1% carbon dioxide is produced, the reaction conditions in said second reaction zone have an over-all exothermic effect such that no external heat is necessary to maintain the aforesaid temperature therein, passing an effluent comprising carbon monoxide from said second reaction zone to said solids separator in which the effluents of said first and said second reaction zones are combined, withdrawing a combined effluent comprising hydrogen and carbon monoxide in a mol ratio between 15 about 0.5:1 and about 2:1 from said solids separator as the product of the process, heat exchanging the aforesaid oxygen and steam with the combined effluents prior to charging the same to the reaction zones in the aforesaid manner and removing a sufficient quantity of finely-divided solids from said second reaction zone substantially at the temperature of said second reaction zone and passing same to said first reaction zone to maintain the temperature therein in the above range.

3. A process for producing a gaseous mixture of hydrogen and carbon monoxide which comprises passing steam and finely-divided carbon-containing material 20 through a first reaction zone at a velocity effective to move said finely-divided carbon-containing material as a fluidized mass through said first reaction zone in the direction of flow of the gases therethrough, maintaining in said first reaction zone endothermic conditions of reaction and a temperature between about 1300 and about 1700° F. such that hydrogen and carbon monoxide are produced as the principal products of the reaction between steam and carbon, withdrawing an effluent from said first reaction zone comprising hydrogen, carbon monoxide, entrained ash and unconverted carbon-containing material and passing same at a relatively high velocity of at least 5 feet per second to a solids separator in which solids are separated from the effluent, introducing fresh carbon-containing material into said effluent from said first reaction zone, passing solids from said solids separator into a second reaction zone, passing pure oxygen upward through said second reaction zone at a velocity such that finely-divided solids are maintained in a fluidized condition therein, maintaining said second reaction zone under exothermic conditions of reaction at a temperature between about 1800 and about 2000° F. such that a product gas containing a major amount of carbon monoxide and a minor amount of less than about 1% carbon dioxide is produced, the reaction conditions in said second reaction zone have an overall exothermic effect such that no external heat is necessary to maintain the aforesaid temperature therein, passing an effluent comprising carbon monoxide from said second reaction zone to said solids separator in which the effluents from said first and second reaction zones are combined, withdrawing a combined effluent comprising hydrogen and carbon monoxide from said solids separator as the product of the process, heat exchanging the aforesaid oxygen and steam with the combined effluents prior to charging the same to the reaction

zones in the aforesaid manner, and removing a sufficient quantity of finely-divided solids from said second reaction zone substantially at the temperature of said second reaction zone and passing same to said first reaction zone to maintain the temperature therein in the above range.

4. A process for producing a gaseous mixture comprising hydrogen and carbon monoxide which comprises supplying pure oxygen for passage upwardly through a mass of finely divided carbon containing solid material in a first reaction zone at a velocity effective to suspend said solids in a fluidized condition, reacting a portion of the carbon containing solids with oxygen containing gas in the first reaction zone at a temperature of about 1800° to about 2000° F. thus producing a product gas containing a major amount of carbon monoxide and a minor amount of less than about 1% carbon dioxide, the reaction conditions in said first reaction zone have an overall exothermic effect such that no external source of heat is necessary to maintain the aforesaid temperature therein, passing steam upwardly through a mass of finely divided carbon containing solid material in a second reaction zone at a velocity effective to suspend said solids in a fluidized condition, reacting the solids and steam in the second reaction zone at a temperature of about 1300° to about 1700° F. thus producing carbon monoxide and hydrogen as the principal products of the reaction, withdrawing a portion of carbon containing solids from the first reaction zone and passing same to the second reaction zone wherein the reaction conditions produce endothermic heat effects in a quantity sufficient to maintain the aforesaid temperature therein, separately removing effluents from said first and second reaction zones as the product of the process containing entrained finely divided ash and unconverted carbon containing material, passing said separate effluents to a common solids separating zone wherein the effluents are combined and the ash and carbon material are removed from the effluents, and heat exchanging the aforesaid oxygen stream and steam with the combined effluents prior to charging the same to the reaction zones in the aforesaid manner.

5. A process for producing a gaseous mixture comprising hydrogen and carbon monoxide which comprises supplying pure oxygen for upward flow through a mass of finely divided carbon containing solid material in a first reaction zone at a velocity effective to suspend the solids in a fluidized condition, reacting a portion of the carbon containing solids with oxygen in the first reaction zone at a temperature of about 1800° to about 2000° F. thus producing a product gas containing substantially all carbon monoxide and less than about 1% carbon dioxide, the reaction conditions in said first reaction zone have an overall exothermic effect such that no external source of heat is required to maintain the aforesaid temperature therein, passing steam upwardly through a mass of finely divided carbon containing solid material in a second reaction zone at a velocity effective to suspend said solids in a fluidized condition, reacting the solids and steam in the second reaction zone at a temperature of about 1500° to about 1700° F. thus producing principally carbon monoxide and hydrogen and less than about 5% carbon dioxide, methane and water in the reaction product effluent, withdrawing a portion of carbon containing solids from the first reaction zone and passing same to the second reaction zone wherein the reaction conditions produce endothermic heat effects in a quantity sufficient to maintain the aforesaid temperature therein, separately removing effluents from said first and second reaction zones as the product of the process containing entrained finely divided ash and unconverted carbon containing material, passing said separate effluents to a common solids separating zone wherein the effluents are combined and the ash and carbon material are removed from the effluents, and heat exchanging the aforesaid oxygen stream and steam with the combined

effluents prior to charging same to the reaction zones in the aforesaid manner.

6. A process for producing a gaseous mixture comprising hydrogen and carbon monoxide which comprises supplying pure oxygen for passage upwardly through a mass of finely divided carbon containing solid material in a first reaction zone at a velocity effective to suspend the solids in a fluidized condition, reacting a portion of the carbon containing solids with the oxygen in the first reaction zone at a temperature of about 1800° to about 2000° F. thus producing a product gas containing a major amount of carbon monoxide and a minor amount of less than about 1% carbon dioxide, the reaction conditions in said reaction zone have an overall exothermic effect such that no external source of heat is necessary to maintain the aforesaid temperature therein, passing steam upwardly through a mass of finely divided carbon containing solid material in a second reaction zone at a velocity effective to suspend said solids in a fluidized condition, reacting the solids and steam in the second reaction zone at a temperature of about 1300° to about 1700° F. thus producing a major amount of carbon monoxide and hydrogen and a minor amount of carbon dioxide, withdrawing a portion of carbon containing solids from the first reaction zone and passing same to the second reaction zone wherein the reaction conditions produce endothermic heat effects in a quantity sufficient to maintain the temperature therein, passing the effluent comprising carbon monoxide, carbon dioxide and hydrogen from the second reaction zone to a carbon dioxide absorber in which the carbon dioxide is removed therefrom, recycling the carbon dioxide thus removed to the first reaction zone for conversion to carbon monoxide, combining the effluent from the second reaction zone substantially free of carbon dioxide and the effluent comprising carbon monoxide from the first reaction zone as the product of the process and heat exchanging the aforesaid oxygen stream and steam with the combined effluents prior to charging the same to the reaction zones in the aforesaid manner.

7. A process for producing a gas of relatively high heat value comprising hydrogen, carbon monoxide and methane from coal which comprises supplying pure oxygen for passage upwardly through a mass of finely divided carbon-containing material in a first reaction zone at a velocity effective to suspend said coal in a fluidized condition, reacting a portion of the carbon with the oxygen in the first reaction zone at a temperature of about 1800° to about 2000° F. thus producing a product gas containing a major amount of carbon monoxide and a minor amount of less than about 1% carbon dioxide, the reaction conditions in said first reaction zone have an overall exothermic effect such that no external source of heat is necessary to maintain the aforesaid temperature therein, passing steam upwardly through a mass of finely divided carbon containing material in a second reaction zone at a velocity effective to suspend said carbon-containing material in a fluidized condition, reacting the carbon and steam in the second reaction zone at a temperature of about 1300° to about 1500° F. thus producing hydrogen, carbon monoxide, methane and carbon dioxide as the principal products of the reaction, withdrawing a portion of finely divided solids from the first reaction zone and passing same to the second reaction zone wherein reaction conditions produce endothermic heat effects in a quantity sufficient to maintain the aforesaid temperature therein, introducing fresh coal into a second reaction zone whereby the volatile components of said coal are distilled, removing an effluent comprising hydrogen, carbon monoxide, methane, carbon dioxide and volatile components of the coal from the second reaction zone, condensing the normally liquid volatile components of the coal from the effluent from the second reaction zone, passing the remainder of the effluent from the second reaction zone substantially free of normally liquid volatile components to a carbon dioxide absorber wherein carbon dioxide is

removed from the effluent and is recovered, passing the recovered carbon dioxide to the first reaction zone wherein the carbon dioxide is converted to carbon monoxide, and combining the effluent comprising hydrogen and carbon monoxide from the second reaction zone substantially free from carbon dioxide with an effluent comprising carbon monoxide from the first reaction zone as a product of the process and heat exchanging the aforesaid oxygen and steam with the combined effluents prior to charging the same to the reaction zones in the aforesaid manner.

8. A process for producing a gas of relatively high heating value comprising hydrogen, carbon monoxide and methane from coal which comprises supplying pure oxygen for passage upwardly through a mass of finely divided carbon-containing material in a first reaction zone at a velocity effective to suspend the carbon-containing material in a fluidized condition, reacting a portion of carbon with the oxygen in the first reaction zone at a temperature of about 1800° to about 2000° F. thus producing a product gas containing a major amount of carbon monoxide and a minor amount of less than about 1% carbon dioxide, the reaction conditions in said first reaction zone have an overall exothermic effect so that no external source of heat is necessary to maintain the aforesaid temperature therein, passing steam upwardly through a mass of finely divided carbon-containing material in a second reaction zone at a velocity effective to suspend the carbon-containing material in a fluidized condition, reacting the carbon and steam in the second reaction zone at a temperature of about 1300° to about 1500° F. thus producing hydrogen, carbon monoxide, methane and carbon dioxide as the principal products of the reaction, withdrawing a portion of finely divided solids from the first reaction zone and passing same to the second reaction zone wherein the reaction conditions produce endothermic heat effects in a quantity sufficient to maintain the aforesaid temperature therein, removing an effluent comprising hydrogen, carbon monoxide, methane and carbon dioxide from the second reaction zone, passing the effluent from the second reaction zone to a carbon dioxide absorber wherein the carbon dioxide is separated from the effluent and recovered, passing the recovered carbon dioxide to the first reaction zone wherein it is converted to carbon monoxide, and combining the effluent comprising hydrogen, methane and carbon monoxide from the second reaction zone substantially free of carbon dioxide with the effluent comprising carbon monoxide from the first reaction zone as the product of the process and heat exchanging the aforesaid oxygen and steam with the combined effluents prior to charging the same to the reaction zones in the aforesaid manner.

9. A process for the gasification of coal and the recovery of volatile components therefrom which comprises supplying pure oxygen for passage upwardly through a mass of finely divided carbon containing solid material in a first reaction zone at a velocity effective to suspend the solids therein, reacting a portion of the carbon with the oxygen in the first reaction zone at a temperature of about 1800° to about 2000° F. suitable for the production of a product gas containing a major amount of carbon monoxide and a minor amount of less than about 1% carbon dioxide, the reaction conditions in said first reaction zone have an overall exothermic effect such that no external heat is necessary to maintain the required temperature therein, simultaneously passing steam upwardly through a mass of finely divided carbon containing solid material in a second reaction zone at a velocity effective to suspend the solids therein, reacting steam with part of the carbon material in the second reaction zone at a temperature of about 1300° to about 1700° F. suitable for producing principally carbon monoxide and hydrogen, passing the effluent from the second reaction zone upwardly through a mass of finely divided coal in a distillation zone at a velocity effective to suspend the coal in a fluidized condition, circulating finely divided solids be-

tween the reaction zones to maintain the desired temperatures therein, introducing fresh coal into the distillation zone wherein volatile components of the fresh coal are distilled, passing finely divided carbon containing material

5 from the distillation zone to one of the reaction zones, removing the effluent comprising hydrogen, carbon monoxide and volatile components of the coal from the distillation zone, recovering volatile components of the coal from the effluent containing the same, removing an effluent

10 comprising carbon monoxide from the first reaction zone and combining the same with the hydrogen and carbon monoxide of the effluent substantially free of volatile components from the distillation zone as the product of the process and heat exchanging the aforesaid oxygen stream and steam with the combined effluents prior to charging the same to the reaction zones in the aforesaid manner.

10. A process for the gasification of coal and the recovery of volatile components therefrom which comprises supplying pure oxygen for passage upwardly

20 through a mass of finely divided carbon containing solid material at a velocity effective to suspend the solids therein, reacting part of the carbon with the oxygen in the first reaction zone at a temperature of about 1800° to about 2000° F. thus producing a product gas containing a major amount of carbon monoxide and a minor amount of less than about 1% carbon dioxide, the reaction conditions in the first reaction zone have an overall exothermic effect such that no external source of heat

25 is necessary to maintain the aforesaid temperature therein, simultaneously passing steam upwardly through a mass of finely divided carbon containing solid material in a second reaction zone at a velocity effective to suspend the solids therein, reacting part of the carbon with steam in the second reaction zone at a temperature of about

30 1500° to about 1700° F. thus producing carbon monoxide and hydroxen as the principal products of the reaction, the reaction conditions in the second reaction zone producing endothermic heat effects and thus requiring heat from external sources to maintain the desired temperature therein, circulating finely divided solids between said reaction zones to maintain the desired temperatures therein, separating finely divided hot solids at an elevated temperature from gases of said second reaction zone and passing same to a distillation zone, introducing fresh coal into said distillation zone whereby the

35 fresh coal is contacted with the hot solids and thus volatile components of the fresh coal are distilled therefrom, removing a gaseous effluent comprising volatile components of the fresh coal from said distillation zone and recovering same as a product of the process, recirculating a portion of the gaseous effluent from said distillation zone to maintain the solids therein in an aerated condition, removing finely divided carbon-containing material substantially free from volatile components from

40 said distillation zone and passing same to one of said reaction zones, separately withdrawing effluents from said reaction zones and combining same as a product of the process and heat exchanging the aforesaid oxygen and steam with the combined effluents prior to charging the same to the reaction zones in the aforesaid manner.

45 11. A process for producing normally liquid organic compounds from coal which comprises supplying pure oxygen for passage upwardly through a mass of finely divided carbon-containing material at a velocity effective to suspend the same in a fluidized condition, reacting part of the carbon with the oxygen in the first reaction zone at a temperature of about 1800° to about 2000° F. thus producing a product gas containing a major amount of carbon monoxide and a minor amount of less than

50 about 1% carbon dioxide, the reaction conditions in the first reaction zone have an overall exothermic effect such that no external source of heat is necessary to maintain the aforesaid temperature therein, passing steam upwardly through a mass of finely divided carbon-containing material in a second reaction zone at a velocity effec-

55 60

76

tive to suspend the finely divided material in a fluidized condition, reacting the steam and carbon in the second reaction zone at a temperature of about 1500° to about 1700° F. thus producing hydrogen and carbon monoxide as the principal products of the reaction, circulating finely divided solid material between said reaction zones to maintain the temperatures therein within the aforesaid ranges, separately removing effluents from said first and second reaction zones containing entrained finely divided ash and unconverted carbon containing material, passing said separate effluents to a common solids separator in which the effluents are combined and ash and carbon containing materials are removed from the effluents, heat exchanging the aforesaid oxygen and steam with the combined effluents prior to charging the same to the reaction zones in the aforesaid manner, passing said combined effluents after heat exchange with said oxygen and steam to a synthesis reaction zone in which hydrogen and carbon monoxide are converted to normally liquid organic compounds, removing an effluent comprising normally liquid organic compounds, methane and carbon dioxide from said synthesis reaction zone, separating normally liquid organic compounds from the effluent of said synthesis reaction zone as the product of the process, separating the carbon dioxide from the normally gaseous components of said effluent from said synthesis reaction zone, passing the carbon dioxide thus separated to the said first reaction zone, and passing normally gaseous components of said effluent from said synthesis reaction zone substantially free from carbon dioxide to said second reaction zone.

12. A process for producing normally liquid organic compounds from carbon containing solid materials which comprises supplying pure oxygen for passage through a mass of finely divided carbon containing solid material in a first reaction zone at a velocity effective to suspend the solid material therein, reacting part of the carbon with oxygen in the first reaction zone at a temperature of about 1800° to about 2000° F. thus producing a product gas containing a major amount of carbon monoxide and a minor amount of less than about 1% carbon dioxide, passing steam through a mass of finely divided carbon containing solid material in a second reaction zone at a velocity effective to suspend the carbon material therein, reacting carbon with steam in the second reaction zone at a temperature of about 1500° to about 1700° F. thus producing hydrogen and carbon monoxide as the principal products of the reaction, withdrawing a portion of the finely divided solids from the first reaction zone and passing same to the second reaction zone wherein the reaction conditions produce endothermic heat effects in a quantity sufficient to maintain the desired temperature therein, separately removing effluents from said first and said second reaction zones and combining same, heat exchanging the aforesaid oxygen and steam with the combined effluents prior to passing the same to the reaction zones in the aforesaid manner, passing said combined effluents to a synthesis reaction zone in which hydrogen and carbon monoxide are converted to normally liquid organic compounds, removing an effluent comprising normally liquid organic compounds, methane and carbon dioxide from the effluent of said synthesis reaction zone as a product of the process, separating the carbon dioxide from the normally gaseous components of said effluent from said synthesis reaction zone, and passing the carbon dioxide thus separated to said first reaction zone.

13. A process for producing normally liquid organic compounds from carbon containing solid material which comprises supplying pure oxygen for passage through carbon containing solid material in a first reaction zone, reacting part of the carbon with the oxygen in the first reaction zone at an elevated temperature about 1800° to 2000° F. suitable for producing a product gas containing a major amount of carbon monoxide and a minor amount

of less than about 1% carbon dioxide, the reaction conditions in the first reaction zone are such that an overall exothermic heat effect is produced, passing steam through a mass of carbon containing solid material in a second reaction zone under conditions including a temperature of about 1300° to 1700° F. suitable for producing hydrogen and carbon monoxide as the principal products of the reaction, the reaction conditions in the second reaction zone are such that an overall endothermic heat effect is produced, transferring the exothermic heat produced in the first zone to the second reaction zone by passing finely divided carbon-containing material from the former zone to the latter zone in order to maintain the desired temperature therein, separately removing effluents from said first and said second reaction zones and combining same, heat exchanging the oxygen and steam with the combined effluents prior to passing the same to the reaction zones in the aforesaid manner, passing said combined effluents to a synthesis reaction zone in which hydrogen and carbon monoxide are converted to normally liquid organic compounds, removing an effluent comprising normally liquid organic compounds, methane and carbon dioxide from said synthesis reaction zone, separating normally liquid organic compounds from the effluent of said synthesis reaction zone as a product of the process, and passing normally gaseous components of said effluent containing carbon dioxide from said synthesis reaction zone to said first reaction zone.

14. A process for producing a gaseous mixture comprising carbon monoxide and hydrogen which comprises supplying pure oxygen for passage upwardly through a mass of ash-producing finely divided carbon containing solid material in a first reaction zone at a velocity effective to suspend the solids in a fluidized condition, reacting a portion of carbon containing solids with oxygen in the first reaction zone at a temperature of about 1800° to about 2000° F. thus producing a product gas containing a major amount of carbon monoxide and a minor amount of less than about 1% carbon dioxide, the reaction conditions in said first reaction zone have an overall exothermic effect such that no external source of heat is necessary to maintain the aforesaid temperature therein, passing steam upwardly through a mass of ash-producing finely divided carbon containing solid material in a second reaction zone at a velocity effective to suspend the solids in a fluidized condition, reacting the steam and part of the solid material in the second reaction zone at a temperature of about 1300° to about 1700° F. thus producing principally carbon monoxide and hydrogen, withdrawing a portion of solid material from the first reaction zone and passing same to the second reaction zone wherein the reaction conditions produce endothermic effects in a quantity sufficient to maintain the desired temperature in the second reaction zone, withdrawing a portion of finely divided solid material including carbon from the second reaction zone and passing same to a third reaction zone wherein the carbon is reacted with oxygen containing gas and completely converted to an effluent comprising carbon monoxide, carbon dioxide, unreacted oxygen and finely divided ash, the quantity of solid material withdrawn from the second reaction zone and passed to the third reaction zone is sufficient to prevent substantially ash build-up in the system, separating the ash from the effluent of the third reaction zone and discharging the same from the system, recycling the effluent containing carbon dioxide and substantially free of ash to the first reaction zone, separately removing effluents from the first and second zones and combining same as the product of the process and heat exchanging the aforesaid oxygen and steam with the combined effluents prior to charging the same to the reaction zones in the aforesaid manner.

15. The process of claim 4 wherein fresh coal is charged to the first reaction zone.

16. The process of claim 4 wherein fresh coal is charged to the second reaction zone.
